DESIGN FOR A LIGHTING FIXTURE

Herbert J. Graham, Philadelphia, Pa., assignor to Electric Service Supplies Company, Philadelphia, Pa., a corporation of Pennsylvania

Application March 28, 1941, Serial No. 99,950

Term of patent 14 years

To all whom it may concern:

Be it known that I, Herbert J. Graham, a citizen of the United States and a resident of Philadelphia, county of Philadelphia, State of Pennsylvania, have invented a new, original, and ornamental Design for a Lighting Fixture, of which the following is a specification, reference being had to the accompanying drawing, forming a part thereof, wherein:

I claim:

The ornamental design for a lighting fixture,
as shown.

HERBERT J. GRAHAM.
